UNITED STATES PATENT OFFICE

ANDREW EKMAN, OF GRAND RAPIDS, MICHIGAN, ASSIGNOR TO GRAND RAPIDS BRASS COMPANY, OF GRAND RAPIDS, MICHIGAN

LATCH

Application filed April 8, 1929. Serial No. 353,318.

The main objects of this invention are:

First, to provide a reversible latch well adapted for refrigerators and the like, which is very simple in structure and at the same time strong and durable.

Second, to provide a reversible latch in which the bolt is automatically locked in its retracted position to be released by engagement with a tappet as the door is swung to closed position.

Objects pertaining to details and economies of my invention will definitely appear from the description to follow. The invention is defined in the claims.

15 A structure which embodies the features of my invention is clearly illustrated in the accompanying drawing in which:

Fig. 1 is a fragmentary front elevation of a refrigerator door and casing having a latch 20 and keeper applied thereto in operative relation, the latch casing being shown in section to disclose the arrangement of parts therein, the bolt pivot also being shown in section.

Fig. 2 is a fragmentary front elevation 25 corresponding to that of Fig. 1 with the latch in retracted position.

Fig. 3 is a fragmentary view partially in section on line 3—3 of Fig. 1.

Fig. 4 is a fragmentary side elevation with 30 the parts in the position shown in Fig. 2.

Fig. 5 is a detail section on a line corresponding to line 5—5 of Fig. 3.

In the accompanying drawing 1 represents 35 a refrigerator casing and 2 a door. The latch housing 3 is provided with attaching flanges 4 and with a base plate 5. The front wall 6 of the housing has an elongated opening 7 therein while the rear wall has an opening 8. The lever-like bolt 9 is arranged through both 40 of these openings. The bolt is provided with a handpiece 10 at its rear end and with a strike engaging roller 11 at its front end.

The bolt 9 has an elongated pivot engaging opening 12 coacting with the pivot 13 on 45 the housing so that the bolt has a pivotal and longitudinal movement on the pivot. This pivot is arranged through a tongue-like support 14 which is formed by striking in a portion of the rear wall 15 of the housing in forming the opening 8 therein. The pivot

is provided with a head 16 and is upset at 17 into the base plate, constituting a tie or securing member for the base plate. The pivot is thus effectively supported without defacing the top of the housing.

The bolt is provided with a longitudinal recess 37 opening to the pivot so that the pivot constitutes a thrust member for the coiled spring 18 arranged within the recess, this spring acting to urge the bolt yieldingly forward.

The T-shaped toggle member 19 is pivoted at 20 on the bolt to engage the front wall 6 of the housing which constitutes an abutment therefor. This toggle member 19 has a flat 35 face 21 which bears against the abutment, holding the bolt yieldingly in its central strike engaging position, and it is also inclined at 22 at each end of this flat portion 21, thereby forming spaced fulcrum points 70 23 upon which the toggle member rocks. The inclined portions 22 engage the abutment when the latch is in retracted position as shown in Fig. 2.

The cross portion of the toggle member is 75 of such length that the side walls of the housing serve to limit its lateral movement, the end of the toggle member engaging the side wall during the initial movement of the bolt from its central position.

The strike 24 is provided with a downwardly and inwardly inclined face 25 with which the roller 11 engages, acting to draw the door against its jamb. The strike is provided with a tappet 26 with which the 85 bolt engages in the event of the door being closed with the latch in retracted position. This tappet has a rearwardly and downwardly inclined face 27 so that the end of the bolt is swung downwardly to break the toggle 90 and the bolt is forced into engagement with the keeper by means of the spring.

By this arrangement of parts the parts may be of substantial size, even in a compact structure. Further, comparatively few parts 95 are required and they are arranged so that there is a minimum of wear thereon.

I have illustrated and described my improvements as embodied in refrigerator latches. My improvements are, however,

readily adapted for use in various relations.

Having thus described my invention what I claim as new and desire to secure by Letters Patent is:

- 5 1. In a latch, the combination of a housing having openings in its front and rear walls, a pivot carried by said housing, a bolt arranged through said openings and having an elongated pivot opening engaged by said pivot whereby the bolt is supported for pivotal and longitudinal movement, said bolt having a recess open to said pivot, a coiled spring arranged in said recess to engage said pivot, and a toggle member pivotally mounted on said bolt to engage the front wall of the housing, the housing engaging a face of said toggle member having a flat central portion and inclined portions at each end thereof, the side walls of the housing coacting with the ends of the toggle member to limit its lateral movement whereby the bolt is yieldingly held in a central position or at either end of its stroke. 10 15 20 25 30 35 40 45 50 55 60 65 70 75 80 85 90 95 100 105 110 115 120 125 130

2. In a latch, the combination of a housing having openings in its front and rear walls, a pivot carried by said housing, a bolt arranged through said openings and having an elongated pivot opening engaged by said pivot whereby the bolt is supported for pivotal and longitudinal movement, said bolt having a recess open to said pivot, a coiled spring arranged in said recess to engage said pivot, and a toggle member pivotally mounted on said bolt to engage the front wall of the housing, the housing engaging a face of said toggle member having a flat central portion and inclined portions at each end thereof. 35 40 45 50 55 60 65 70 75 80 85 90 95 100 105 110 115 120 125 130

3. In a latch, the combination of a housing having openings in its front and rear walls, a pivot carried by said housing, a bolt arranged through said openings and having an elongated pivot opening engaged by said pivot whereby the bolt is supported for pivotal and longitudinal movement, said bolt having a recess open to said pivot, a coiled spring arranged in said recess to engage said pivot, and a toggle member pivotally mounted on said bolt and having an angled face engaging the front wall of the housing. 45 50 55 60 65 70 75 80 85 90 95 100 105 110 115 120 125 130

4. In a latch, the combination of a housing having openings in its front and rear walls, a pivot carried by said housing, a bolt arranged through said openings and having an elongated pivot opening engaged by said pivot whereby the bolt is supported for pivotal and longitudinal movement, said bolt having a recess open to said pivot, a coiled spring arranged in said recess to engage said pivot and bolt, and a member pivotally mounted on said bolt at the front of said bolt pivot and having spaced fulcrums disposed on opposite sides of its longitudinal center to engage the front wall of the housing. 55 60 65 70 75 80 85 90 95 100 105 110 115 120 125 130

5. In a latch, the combination of a housing longitudinal movement, said bolt having a recess open to said pivot, a coiled spring arranged in said recess to engage said pivot, and a toggle member pivotally mounted on said bolt and having spaced fulcrums engaging the front wall of the housing, the side walls of the housing coacting with the toggle member to limit its lateral movement whereby when both the fulcrums are engaged with the wall of the housing the bolt is held yieldingly in a central position, the fulcrums being positioned so that the axis of the pivot for the toggle member to the bolt swings across a plane through the axis of the bolt pivot and the fulcrum point when the bolt is swung to and from retracted position. 70 75 80 85 90 95 100 105 110 115 120 125 130

6. In a latch, the combination of a housing, a pivot carried by said housing, a bolt projecting from said housing and having an elongated pivot opening engaging said pivot whereby the bolt is supported for pivotal and longitudinal movement, said bolt having a recess open to said pivot, a coiled spring arranged in said recess to engage said pivot, and a toggle member pivotally mounted on said bolt and having spaced fulcrums engaging the front wall of the housing, the fulcrums being positioned so that the axis of the pivot for the toggle member to the bolt swings across a plane through the axis of the bolt pivot and the fulcrum point when the bolt is swung to and from retracted position. 90 95 100 105 110 115 120 125 130

7. In a latch, the combination with a support, of a bolt mounted on said support for pivotal and longitudinal movement, an abutment on said support, a toggle member pivotally mounted on said bolt in spaced relation to its pivot and in the plane of the longitudinal center of the bolt and provided with spaced fulcrum points disposed on opposite sides of its longitudinal center and coacting with said abutment, and a spring engaging said bolt and acting to urge said toggle against said abutment. 105 110 115 120 125 130

8. In a latch, the combination with a support, of a bolt mounted on said support for pivotal and longitudinal movement, an abutment on said support, a toggle member pivotally mounted on said bolt in spaced relation to its pivot and in the plane of the longitudinal center of the bolt and provided with spaced fulcrum points disposed on opposite sides of its longitudinal center and coacting with said abutment, and a spring acting to urge said toggle against said abutment. 120 125 130

9. In a latch, the combination with a support, of a bolt mounted on said support for pivotal and longitudinal movement, an abutment on said support, a toggle member pivotally mounted on said bolt in spaced relation to its pivot and in the plane of the longitudinal center of the bolt and provided with spaced fulcrum points disposed on opposite sides of its longitudinal center and coacting with said abutment, and a spring acting to urge said toggle against said abutment. 130

to its pivot and in the plane of the longitudinal center of the bolt and provided with a fulcrum coating with said abutment, and a spring acting on said bolt to urge said toggle member against said abutment, said fulcrum being positioned so that the axis of the pivot for the toggle to the bolt swings across a plane through the axis of the bolt pivot and the fulcrum point when the bolt is swung to and from retracted position, the toggle member being provided with abutment engaging portions at each side of its fulcrum.

10. In a latch, the combination with a housing comprising a top and an integral side wall, a portion of said wall being struck inwardly to form a bolt opening and providing a pivot support, said pivot support having a pivot opening therein, a bolt, and a pivot for said bolt arranged through said opening in said support and provided with a head disposed between the support and the top of the housing.

11. In a latch, the combination of a support, a bolt mounted on said support for pivotal and longitudinal movement, a toggle member pivotally mounted on said bolt, an abutment on said support with which said toggle is rockingly associated, said toggle having an angled abutment engaging face, and a spring coating with said bolt to urge said toggle member against its abutment.

12. In a latch, the combination with a support, of a bolt mounted on said support for pivotal and longitudinal movement, a toggle member pivotally mounted on said bolt in spaced relation to said bolt pivot and in the longitudinal center of the bolt and provided with spaced fulcrum points engaging said support, said support being provided with parts coating with the ends of the toggle member to limit its lateral movement, and a spring coating with said bolt to urge said toggle member against its coating abutment on said support.

45 In witness whereof, I have hereunto set my hand.

ANDREW EKMAN.
